UNITED STATES PATENT OFFICE.

EUGENE M. MIX AND JAMES E. MIX, OF BUFFALO, NEW YORK.

LATCH.

SPECIFICATION forming part of Letters Patent No. 283,268, dated August 14, 1883.

Application filed May 8, 1883. (Model.)

To all whom it may concern:

Be it known that we, EUGENE M. MIX and JAMES E. MIX, citizens of the United States, residing at Buffalo, in the county of Erie and State of New York, have invented new and useful Improvements in Latches, of which the following is a specification.

This invention relates to improvements in that class of latches which are provided with two independent knob-shanks for actuating the latch-bolt, especially to that class wherein the knob-shanks have hooked ends to engage the latch-case, and cams to operate on the sliding yoke which connects with the latch-bolt.

The object of our invention is to provide means whereby we are enabled to retain the ordinary rotating hubs in knob-latches, and at the same time make a perfect adjustment to thicknesses of doors without the necessity of employing the usual spindle, side knob-screws, or other fastening devices, and dispensing with the employment of washers. This object we accomplish in the manner and by the means hereinafter described and claimed, and as illustrated in the accompanying drawings, in which—

Figure 1 is a broken side view of a mortise-lock latch applied to a door and embodying our invention, the knob-shanks being omitted; Fig. 2, a sectional view on the line *xx* of Fig. 1, the knob-shanks being in position; Fig. 3, perspective views of the knob-shanks, the yokes, the latch-bolt, and the yoke-operating hubs; Fig. 4, a detached perspective view of one of the hubs; and Fig. 5, a perspective view, showing a modification of the invention.

The lock and latch mechanism may be of any suitable or desirable construction, and therefore we do not deem it essential to further illustrate the interior mechanism of the lock and latch casing. The latch-bolt number 1, as usual, is impelled to its outer position by a coiled spring, and is retracted by a sliding yoke. In Figs. 1, 2, and 3 there are shown two yokes, 2, arranged side by side, to engage the latch-bolt, each yoke being independently moved by one of the knob-shanks, 3, through the instrumentality of a hub, 4, having lugs 5, to engage with projections 6 on the arms 7 of each yoke. The hubs 4 are provided with angular sockets 8, at the inner edge of each of which is a lateral recess, 9, with which engages

the hook 10 on the inner end of the knob-shanks 3, by which means the knob-shank is held against displacement by being drawn outward, and the latch-bolt can be moved through the rotation of the hubs. The hubs are provided, as usual, with annular rims 11, adapted to rotate in socket-bearings in the side walls of the latch-casing, and the knob-shanks are cylindrical, except at their inner ends, where they are made angular to fit the angular sockets in the hubs. The knob-shanks are supported and steadied in proper working position by passing through socket-bearings 12, commonly called a "rose," in the escutcheons 13, the latter being attached to the door by screws or otherwise.

In applying the knob-shanks, after the latch-casing has been secured in its receiving-mortise they are passed through the escutcheons until the inner portions of the knobs rest against the socket-bearings or rose 12, and then the shanks are inserted into the latch-casing and tipped forward until their hooked ends 10 engage the lateral recesses 9 at the inner edge of their angular sockets, when the knob-shanks are turned back into line with each other and the escutcheon firmly secured in position, leaving the knob-shanks in the position shown in Fig. 2. The parts being now in proper relative position, either one of the hubs can be rotated by its knob-shank, thereby actuating its own yoke to operate the latch-bolt, one shank being entirely free of the other and the motion of one not changing or affecting the position of the other.

In order to resist the strain on the cover-plate 14 of the latch-case adjacent to the hub, which results from pulling and otherwise manipulating the knob-shank at that side of the door, we provide the cover-plate with an inwardly-projecting flange, 15, directly in rear of the hub, and secure this flange by a screw, 16, passing through the rear edge of the latch-casing into said flange, as shown in Fig. 2, the cover-plate being also secured at or near its center by the usual screws, 17.

In Fig. 5 we have shown the invention applied to a single hub for operating the ordinary yoke which actuates the latch-bolt. The hub in this instance is provided with a recess, 9, in the form of an open slot formed through the hub, and the hooked ends of both knob-

shanks engage this recess. It will, of course, be obvious that in this construction, while the knob-shanks are independent, the movement of one in rotating the hub to actuate the latch-bolt imparts motion to the other through the hub; but still the knob-shanks possess the advantage of being separate. The single hub renders the lock-latch less expensive and complicated, and enables the invention to be applied to the cheap grades of mortise-locks, and it can thus be generally used without increasing the cost of the locks in any particular. It will be evident that the invention can be applied to lock-latches already constructed or in use by simply removing therefrom the ordinary hub and applying our hub or hubs, with which the independent hooked knob-shanks can be made to engage or connect; and, finally, where a knob-latch is provided with a hub and hooked knob-shanks, as in our invention, the usual through-spindle can be used if occasion demands.

Instead of so constructing the parts that the hooks on the ends of the independent knob-shanks engage a recess in the rotating hub, such hooks can be made to engage the inner face of the lock-casing, and the angular ends 18 of the shanks caused to enter the angular socket 8 in the hub or hubs 4, as shown in Fig. 5.

We are aware that independent knob-shanks have heretofore been provided with projections at their inner ends to engage the side walls of the latch-casing, and also that rotating hubs have been employed to actuate the latch-bolt; but we are not aware that a rotating hub has been so combined with independent shanks having hooked ends to prevent their outward displacement, such shanks entering the hub at their inner ends for rotating said hubs. This materially simplifies the construction of the latch, and consequently renders its manufacture comparatively less expensive than heretofore.

Having thus described our invention, what we claim is—

The combination of independent knob-shanks having hooked inner ends with a rotating hub having a socket to receive such inner end of the shank, substantially as and for the purpose described.

In testimony whereof we have hereunto set our hands in the presence of two subscribing witnesses.

EUGENE M. MIX.
JAMES E. MIX.
